DRYING MACHINE

George M. Marks, Greenville, S.C., assignor to Industrial Heat Engineering Company, a partnership of South Carolina

Filed July 19, 1957, Ser. No. 673,033

2 Claims. (Cl. 263—6)

This invention relates in general to machines for the continuous drying of textiles, paper and like film, and is more particularly directed to a new construction whereby the products of fuel combustion are used directly as the heating agent in one or a plurality of rotating drums on which the fabric or film is in contact.

Drying machines prior to this invention normally used in industry consist of a plurality of hollow cylindrical drums called "heat cans" which are rotated and over which fabrics or films are dried while carried thereby. These drums are normally heated by steam carried therein through packing glands in the journals on which the drums are rotated. Thus, the outer surfaces of the drums are heated by conduction. This method of heating is relatively inefficient for several reasons which include the latent heat loss in creating the steam and the relatively high pressure, with its attendant danger, that must be used to obtain desired temperatures. The drums must be constructed to withstand high pressure and the rotary glands connecting the drums are often troublesome from leakage. Furthermore, since it is desirable to have uniform heat distribution on the outer surface of the drums the steam condensate accumulation inside of the drums is a serious difficulty not only causing non-uniform heating but additional provisions must be made for its removal.

The present invention embraces construction which overcome the above difficulties by supplying directly within each of the drums a burner means for the combustion of a pre-mixture of air and combustible gas. The fuel is usually in the form of a natural, butane, or like gas. The application of a burner and diffusing means within each drum results in attaining temperatures considerably higher than those normally attained by steam accompanied by desirable low pressures in the system to be hereinafter described. The drying drums themselves are less expensive and more efficient due to the relative light-weight construction and suitable operating temperatures are quickly attained without packing glands in their journals. A construction resulting in the direct application of the products of combustion to the inside surfaces of each of the drums comprise the principal object of the invention.

A further object of the invention is the provision of an elongated burner and diffusing means fixed within a rotary drying drum for uniformly heating the outer surfaces of the drum in contact with the fabric or film to be dried.

A further object of the invention is the provision of a burner and diffusion means within a drying drum including supplementary means for controlling the flow of the spent gases resulting from the combustion of fuel within the drying drums.

These and other objects in one embodiment of the invention is described and shown in the appended specification and drawings in which:

Fig. 1 is a side elevation of the drying machine with a portion of the casing cut away.

Fig. 2 is a front elevation of the drying machine taken through section line 2—2, Fig. 1.

Fig. 3 is a cross sectional view of one of the drums taken through section line 3—3, Fig. 1.

Fig. 4 is a cross sectional view taken through section line 4—4, Fig. 3.

2

Fig. 5 is a fragmentary cross sectional view taken through section line 5—5, Fig. 3.

Referring to Figs. 1 and 2, a frame structure 1, rigidly secured to a base 2 resting on a floor, is adapted to support a plurality of rotatable drums 3 positioned with parallel axes and journaled for rotation in hollow bearing assemblies 4 as shown.

All drums are intended to be rotated at the same peripheral speed by an endless chain motor drive means not shown.

The entire machine is enclosed in a case 5 supported a predetermined distance above a floor by legs 6 which provides a ventilation inlet around the bottom of the casing. A stack 7 open to the atmosphere in the top

15 of the casing contains a motor driven suction fan assembly 8 for exhausting products of the combustion generated by burners to be hereinafter described. A header or manifold system 9 is connected to a feeder conduit 10 for conducting a pre-mixture of combustible gas and air into each drum 3. Each valve 11 connected in the header 9 is coupled to each drum for individually controlling the quantity of gas fed thereto.

The fabric or film 12 to be dried is fed into the lower part of the machine in the direction shown by arrow 23 to the lowermost drum 3 by suitable guiding means and then wrapped around each drum, as shown, and passed out of the casing 5 through an elongated slot 13. Suitable means, not shown, are provided for feeding and receiving the material before and after drying.

30 It is apparent that the stagger positioned counter-rotating cylinders, shown Fig. 1, will evaporate moisture from both sides of the material in alternate sequence which results in a high degree of dehydration and permits the material to be driven at a desirable high linear speed.

35 Referring to Fig. 3, one of the drums 3 is shown in cross section supported for rotation by bearing assemblies 4 in which hollow shafts 14 are secured coaxial with end plates 15 of the drum. An elongated burner assembly 16 is secured in offset position from the axis 40 of the drum by suitable fittings 17, 18, 19, 20 and 21 at one end thereof and by fittings 22, 23, 24, 25 and 26 at the opposite end as shown. Fittings 17 and 22 are secured to the main frame by support members 27 and 28.

45 A foraminated flame baffle 29 having a cylindrical shape is retained in the drum in position opposite the burner by supports 30 and 31 secured to fittings 17 and 22 respectively. Damper members 32 and 33 are adjustably secured to drum end plates 15 and provide means for adjusting the area of circular outlets 34 in the end plates 50 13 better shown Fig. 4, for optimum combustion of the fuel.

55 Referring to Figs. 4 and 5, each burner section 35 is provided with a longitudinal passageway 36 which distributes and feeds the combustible pre-mixed gas entering the burner through fitting 17 to a plurality of holes in the burner plates 37 which plates are retained in a cavity in one side of each burner section 35.

60 Referring to Figs. 3 and 5, a spark plug 38 is secured in the end burner section for the initial igniting of the fuel. A suitable electric conductor 39 is carried through the bore of fitting 22 connecting the spark plug and terminating in electric ignition means 40 which in turn is connected to a source of electric energy.

65 In operating and referring to the figures, the fuel feeder conduit 10 is supplied with a pre-mixture of combustible gas and air at a substantially uniform pressure. The gas will then flow through the manifold to the inlet fittings to each burner in each drum under the individual adjustment of valves 11 whereupon the fuel will flow through 70 passageway 36 in the burner and be ignited by the momentary operation of spark plug 38.

Each burner will supply an elongated uniform flame

resulting from the passage of the fuel through the holes in burner plates 37. The flame illustrated in Fig. 4 will impinge upon the foraminated baffle 29 and the resulting diffused heat will be conducted through the wall of the drum 3 to its outer surface in a uniform manner at a high degree of efficiency. The spent products of combustion will pass through the outlets 34 in opposite ends of the drums under the control of the dampers 32 and 33 and thereupon be drawn upward in the casing 5 and exhausted through stack 7 by virtue of the operation of suction fan 8, thus preventing the products of combustion from contaminating or otherwise staining the fabric or film carried on the cylinders. The upward movement of the spent gases to the stack 7 is assisted by the free passage of air into the bottom opening around the casing 5.

When drying certain fabrics it is desirable to maintain different predetermined temperatures in each drum and to this end the individual adjustment of valves 11 and dampers 32 and 33 may be made without sacrificing the uniform heating characteristic of the burner-baffle combination.

When certain heavy fabrics are to be dried the drums may be advantageously modified by substituting a plurality of cylindrically positioned equi-spaced rods forming a cylindrical cage as an alternate for the cylindrical casing 3. Thus the turbulent hot gases will impinge directly on the fabric and evaporate entrained moisture at a higher rate than can be attained by contact with the continuous surface of the casing 3.

Having described my invention, I claim:

1. A machine for the continuous drying of sheet material fed thereto and therefrom comprising means forming a frame, a plurality of hollow cylinders journaled for rotation in said frame about their principal axis and positioned in staggered left and right relation parallel each other, each of said cylinders retained for rotation by a coaxial bearing means on each end thereof secured to said frame and having a coaxial bore therethrough, power drive means coupled to each of said cylinders adapted to rotate each of said left and right cylinders in opposite directions at the same peripheral velocity for carrying said material through said machine in one linear direction with the outer periphery of said left and right cylinders in wrapped contact with corresponding opposite sides of said material when operated, a fixed gas fuel burner means in each of said cylinders including a support means extending through each opposite said bore and secured to said frame for heating each of said cylinders and said material wrapped thereon when energized, said support means forming in part a conduit for conducting gas fuel into each said burner means, a source of pressurized gas fuel, a plurality of valves with the inlets thereof connected to said source of fuel and each outlet thereof connected to each said conduit for independently adjusting a predetermined different flow of said fuel into each of said burner means, an adjustable vent means in the ends of each said cylinder for equalizing the flow of the products of combustion from each end of each of said cylinders and adjusting a predetermined different combustion pressure in each of said cylinders in accordance with the adjustment of corresponding said valves, a casing surrounding said frame and said cylinders having inlet and outlet openings

60

for the passage of said material, said casing having an air inlet at the lower end thereof and a power driven suction means at the upper end thereof for exhausting said products of combustion from said casing when energized whereby said material will be sequentially dehydrated by sequential contact with successive differently heated cylinders dependent upon the relative and corresponding adjustment of said vent means and said valve means when said power means is operated and said burner means and said exhaust means are energized.

2. A machine for the continuous drying of sheet material fed thereto and therefrom comprising means forming a frame, a plurality of hollow cylinder means journaled for rotation in said frame about their principal axes and positioned in staggered left and right relation parallel each other, each of said cylinders retained for rotation by a coaxial bearing means on each end thereof secured to said frame and having coaxial bore therethrough, power drive means coupled to each of said cylinder means adapted to rotate each of said left and right cylinder means in opposite directions at the same peripheral velocity for carrying said material through said machine in one linear direction with the outer periphery of said left and right cylinder means in wrapped contact with corresponding opposite sides of said material when operated, a fixed gas fuel burner means in each of said cylinders including a support means extending through each cylinder opposite said bore and secured to said frame for heating each of said cylinders and the said material wrapped thereon when energized, said support means forming in part a conduit for conducting gas fuel into each said burner means, a source of pressurized gas fuel connected to each said conduit, a casing surrounding said frame and cylinder means including inlet and outlet openings therein for the passage of said material, said casing including an air inlet at the lower end thereof and an exhaust means at the upper end thereof for conducting said products of combustion from said casing, an adjustable vent in each end of each cylinder means for equalizing the flow of the products of combustion from each end of each cylinder means and adjusting the combustion pressure within each of said cylinder means to a predetermined different degree when said burner means are energized whereby said material will be alternately and sequentially dehydrated from opposite sides by said plurality of said cylinder means when fed into and from said machine and said power means is operated and said burner means is energized.
